MATERNITY GIRDLE

Paula Blatt, Cleveland, Ohio

Application October 29, 1954, Serial No. 465,620

2 Claims. (Cl. 2—41)

This invention relates to the general art of wearing apparel and, more particularly, to an improved maternity girdle.

The object of my present invention is to devise a girdle that is capable of effective and comfortable engagement (1) beneath the abdomen of the wearer's body for suitable support thereof during the advancing stages of pregnancy, (2) in the sacroiliac region of the wearer's body so as to provide firm supporting engagement, and (3) beneath her buttock so as to assist in preventing the garment from riding upwardly when stockings are not worn with garters attached to the garment.

Another object is to provide a girdle that will be comfortable during all movements of the wearer's body including forward and rearward bending movements.

Another object is to devise a girdle with a comparatively inexpensive means for permitting stretch both vertically and laterally so as to accommodate itself in a substantially universal manner to the movements of the wearer's body while at the same time affording a snug and firm supporting engagement of the girdle about her body.

Another object is to devise a girdle with firm means of support at the rear part of the buttock of the wearer while permitting suitable stretch at the upper part thereof for easy application of the girdle to the wearer's body and suitable stretch at the lower part during sitting position.

Other objects will appear from the following description and claims when considered together with the drawings.

Fig. 1 is a front view of my present girdle;

Fig. 2 is a rear view thereof;

Fig. 3 is a side view thereof;

Fig. 4 is an enlarged view of a portion thereof;

Fig. 5 is a view taken on line 5—5 of Fig. 4.

Referring to the accompanying drawing, the body of my present girdle comprises the two duplicate front-side-and-rear parts 1 and 2 of satin elastic material which are sewed together at the vertical rear seam 3 and also in overlapping relation at the front, as at 4. The overlapping portions 4 of inverted trapezoidal form are adapted to be positioned in an upwardly and forwardly inclined manner so as to afford most effective supporting engagement beneath the abdominal region of the wearer's body, that is throughout the advancing stages of pregnancy. A longitudinally elastic band 5 of substantial width and corresponding resistance to stretch is sewed at its upper edge about the entire extent of the girdle at the bottom thereof; and a longitudinally elastic band 6 of the same width and character has its lower edge sewed about the girdle at the top thereof, this band terminating at points at the rear of the wearer's body and at the sides of the sacroiliac region. A special form of supporting means, indicated in a general way by reference numeral 7, is provided at the rear and has its ends sewed to the upwardly extending biased end edges of the elastic band 6. Extending also between the rear ends of the band 6, at the lower parts

2

thereof, is the more narrow longitudinally elastic strip 8 which has its lower longitudinal edge sewed to the upper rear substantially horizontal edges of the parts 1 and 2. It is to be noted that the elastic band 8 is free of the part 5 throughout; and the bands 7a and 8 are of such width and are so arranged that they will overlap each other vertically to sufficient extent to ensure such overlapping relationship at all times and during all positions of the wearer's body including forward and rearward bending movements.

Having referred to the general structure of my present girdle, I will now describe the several parts more specifically and explain the advantages of their particular arrangement.

15 The front-side-and-rear parts 1 and 2 are cut upon the bias at approximately forty-five (45) degrees to the direction of the elastic element thereof so as to afford a stretch both vertically and laterally of the body of the girdle. The parts 1 and 2 are narrowed at the front thereof and are placed in overlapping relation to each other in this region, so that this laminated portion will be inelastic in the vertical direction for positive supporting engagement beneath the abdomen of the wearer but will have lateral stretch in a direction about her body.

20 The upper elastic band 6 is so gathered along its front lower edge that it will assume an upwardly and outwardly inclined position, as above referred to, which is adapted to afford most effective and comfortable supporting engagement beneath the abdomen of the body of the wearer during the progressive period of pregnancy; and the elasticity of the band 6 and the adjoining portions of the front-side-and-rear parts 1 and 2 will permit the natural enlargement in the abdominal region to have such

25 support in a manner that will give to the wearer a feeling of utmost security. The front part of band 6 may be provided with an additional lamination 6a of the same material in the region just above and of approximately the same lateral extent as the laminated portion 4, so as to still further contribute to the abdomen-supporting means at this point.

30 By cutting the rear ends of the band 6 on a bias, there is obtained an increased extent for attachment thereto of the ends of the wider elastic band of the rear supporting means 7. This supporting means 7 is of a generally trapezoidal form and comprises two bands 7a each attached at its one end 7b to the end of band 6 and each having its other end portion folded back upon itself in a downward inclined manner and then sewed at its inclined end 7c to itself in such overlapping relation. Then the two adjacent folded ends of the bands 7a are sewed together, as at 7d, along a vertical line at point laterally from the folded ends; and the extreme folded end portions are doubled back and inwardly away from each

35 other and are sewed along lines 7e in such flattened position so as to lie in the same plane and together to constitute a vertically extending rib of substantially rigid nature for supporting engagement in the region of the sacroiliac joint. At the same time, this reinforcing means 40 is capable of a certain degree of stretch in a lateral or horizontal direction so as to permit the necessary yield for comfortable and snug engagement of the girdle as it adapts itself to the body of the wearer. By inclining the end portions of the bands 7a downwardly, as above described, the length of the rib is extended downwardly, as indicated in the present drawing. Also, the inclination of the sewed joints in different directions serves to increase still

45 further the rigidity of this supporting means 7 in directions other than the horizontal or lateral direction and

50 hence its efficiency as a supporting means for the sacroiliac region of the wearer's body is enhanced. It is to be observed that, by virtue of the separation between the bands

7a and 8, there will be permitted all required relative movement between these parts incident to any bending movement of the body of the wearer when the girdle is in position upon her body and without any disturbance of the supporting means 7 in the sacroiliac region. Thus this feature is calculated to ensure a combined sense of comfort and security at all times and under all conditions.

Due to the particular form and arrangement of the several parts, as herein described, the bottom edge of my present girdle will extend angularly and downwardly from the front to the rear thereof, where there is obtained an effective engagement beneath the buttock of the wearer's body. Not only does the lower elastic band 5 have such engagement, but such manner of engagement is afforded also by the adjoining portions of the girdle in this region of the same and thus there is a firm and comfortable engagement throughout the entire lower part of the girdle as a means of distributing such engagement over an increased area of the wearer's body.

Thus my present form of girdle will always be maintained in proper position upon the body of the wearer. The firm engagement of the girdle in the sacroiliac region of the wearer's body will prevent the girdle from slipping downwardly and will also give the wearer a sense of security as well as comfort at all times; and the engagement beneath the buttock of the body of the wearer will prevent the girdle from riding or creeping upwardly so that this garment does not depend upon the wearing of stockings and garters for the purpose of holding the same in position at all times. There will be realized also an effective and comfortable means of engagement beneath the abdominal region of the wearer's body so that, at all times during the successive stages of pregnancy, this supporting means will be capable of expanding and adapting itself to the progressive enlargement of this part of the body of the wearer. As above noted, there will be permitted also an adaptation of the rear part of the girdle during all bending movements of the wearer and without any interference with the position of the firm supporting engagement in the sacroiliac region or with the engaging means beneath the buttock of the wearer. As a still further refinement of my present form of girdle, as herein disclosed, there may be effected stretch in each of the elastic bands 5 and 6 more or less independently of the other so that the functioning of the one in the manner and for the purpose herein explained will not interfere with the functioning of the other while at the same time there will be a co-ordination between these parts of the girdle in the production of a unitary result of a most desirable nature in the class of art to which the present invention relates.

Although, as above explained, it is not necessary to wear garters and stockings for the purpose of holding the present form of girdle down in proper position, yet it is to be understood that this is entirely a matter of choice upon the part of the wearer and that there may be provision for attachment of garters at the bottom of the girdle at any time as may be desired.

Another advantage of my present form of girdle consists in the particular form and arrangement of the satin elastic parts 1 and 2 which, by virtue of being cut on

the bias, will respond in a practically universal manner with the necessary stretch as may be required by the various movements of the body of the wearer; the present structure involving considerably less cost in both material and labor than would be involved in the use of the familiar knit material which in and of itself permits stretch in all directions. Furthermore, the elastic satin affords a firmer and yet softer engagement about the body of the wearer and thus gives her an increased feeling of comfort and security.

What I claim is:

1. A maternity girdle comprising a band adapted to extend beneath the abdomen of the wearer's body and about her hip and sacroiliac regions, and a legless body of elastic material attached to and depending from said band but being free therefrom in the sacroiliac region and being adapted to extend beneath the abdomen of the body of the wearer and about her hips and buttock, and a member extending laterally across the outside of the lower part of said band in the sacroiliac region and having ends attached to said band and having a lower edge attached to said body of elastic material in the sacroiliac region, said member being otherwise free of said band so as to permit said band to remain in substantially fixed position in the sacroiliac region of the wearer's body during all stretching movement thereof, and said member extending upwardly sufficiently to ensure overlying relation of the same at all times with respect to said band.
2. A maternity girdle comprising a band adapted to extend beneath the abdomen of the wearer's body and about her hip and sacroiliac regions, and a legless body having duplicate front-side-and-rear portions of one-way elastic material attached to and depending from said band and adapted to extend about and to cover the hips and buttock of the wearer's body, said front-side-and-rear portions being cut on the bias in opposite directions, the one with respect to the other, so as to afford vertical and lateral stretch throughout the main parts thereof when in position upon the body of the wearer, said front-side-and-rear portions having vertically narrowed parts at the front secured together in overlapping relation to each other and being adapted for engagement exclusively beneath the abdomen of the wearer's body so as to provide an abdomen-supporting means that is free of stretch in the vertical direction and that has stretch in only the lateral direction when in position upon the body of the wearer.
